UNITED STATES PATENT OFFICE.

JOHN T. THOMPSON, OF NEWPORT, KENTUCKY, ASSIGNOR OF ONE-HALF TO THOMAS F. RYAN, OF NEW YORK, N. Y.

GUN.

1,359,635.

Specification of Letters Patent. Patented Nov. 23, 1920.

Application filed March 8, 1920. Serial No. 364,067.

To all whom it may concern:

Be it known that I, JOHN T. THOMPSON, a citizen of the United States, and resident of Newport, in the county of Campbell and 5 State of Kentucky, have invented new and useful Improvements in Guns, of which the following is a specification.

My invention relates to firearms and more particularly to a new and improved locking means for breech closures.

The present invention is particularly applicable to firearms having a reciprocating bolt. Numerous methods have heretofore been devised for locking such bolts, but 15 these methods have in general required a rotary movement either of the bolt proper or of a locking head carried by the bolt on its translatory movement. This combined translatory and rotary movement of the reciprocating breech closure is undesirable since cams and cam-races or equivalent mechanical elements are required to impart the double motion, and an undue complication and multiplicity of parts results. This 20 is even more true where the rotary part is a separate element but carried by the bolt proper and in this latter case there is also the necessity for an undesirably heavy reciprocating element with its consequent 25 shock and jars. Devices which involve these two motions of the bolt or of some of its constituent parts are moreover slower and more uncertain in their action than a device where there is but a single motion of the 30 bolt in locking.

Some devices heretofore devised have endeavored to eliminate the above described difficulties by avoiding a positive lock of any character and having the recoil taken 35 up by a very stiff spring and by the inertia of a heavy breech closure. Such structures are undesirable because of the shock caused by the reciprocation of heavy parts and the jar of the closing of the heavy breech closure impelled by the stiff spring.

Inertia closures are practical only with relatively low breech pressures. The great mass necessary for an inertia breech closure for modern high powered arms with 40 their high breech pressures, prohibits the use of this type of closures with small arms.

In some types of ordnance the problem

has been solved to an extent by the use of a breech closure operating in a direction radial to the axis of the bore. This is practical where the weight of the breech closure is but a small proportion of that of the piece, but is impractical in small arms since the jar of a member operating radially would be not only exceedingly tiring to the 55 operator but fatal to any accuracy of sustained fire.

It is an object of the present invention to provide a breech closure adapted for use in all types of guns in which a reciprocating bolt or similar breech closure is positively locked by a non-reciprocating member and in which the breech closure has no other motion in either locking and unlocking than its reciprocation in opening and closing the 60 chamber. It is an object to provide a breech lock of the character described which is both certain and efficient in operation and simple and relatively inexpensive in manufacture and which is composed of but few 65 parts. It is an additional object to provide a positive lock of the rotary type in which no rotation of the breech closure is required, both locking and unlocking being accomplished by the movement of the lock, 70 the lock being fixed longitudinally relative to the firearm and not accompanying the bolt in its reciprocation. It is also an object to provide a lock of the character described which is particularly adapted for use with 75 automatic or semi-automatic rifles. It is a further object to provide new and improved means for the manual operation of breech locks, the means being particularly adapted for use in connection with the type of lock 80 herein described. Other and further objects 85 will appear as the disclosure proceeds.

My improved lock broadly comprises a bolt reciprocating relatively to the gun breech and a non-reciprocating locking ring 95 encircling the bolt together with interlocking means upon bolt and ring. It further includes means for causing rotation of the lock relative to bolt to perform the locking and unlocking.

This construction avoids the necessity for rotation of the bolt head and thus eliminates the friction occurring between the base of the cartridge and the face of the bolt head in 100

devices where the latter is rotated in locking the breech.

I have illustrated certain specific embodiments of my invention in the accompanying drawings, in which—

Figure 1 is a partly broken away longitudinal cross section with the bolt closed;

Fig. 2 is a view similar to Fig. 1 but with the bolt open;

Fig. 3 is a plan view partly in cross section showing the bolt closed;

Fig. 4 is a cross section on the line 4—4 of Fig. 3;

Fig. 5 is a view taken on line 5—5 of Fig. 1;

Fig. 6 is a view taken on line 6—6 of Fig. 2;

Fig. 7 is a section on line 7—7 of Fig. 3;

Fig. 8 is a view taken on line 8—8 of Fig. 1;

Fig. 9 is a section showing a modified form of lock;

Fig. 10 is a developed view on a reduced scale showing the cams on bolt and ring lock in unlocked position;

Fig. 11 is a view similar to Fig. 10, showing the cams in locking position;

Fig. 12 is a fragmentary view showing the actuator slot;

Fig. 13 is an enlarged view showing the relation of the cams on bolt and ring lock; and

Fig. 14 is a section showing the manual lock opening means.

The form of gun shown in the drawings comprises the receiver member 16 having the cartridge chamber 17, the ejection opening 18, the magazine opening 19 and lock chamber 20. The lock chamber is closed by the member 21, and the rear of the receiver has the recoil housing 22 attached thereto.

The receiver 16 is longitudinally chambered to receive the bolt 23 which has formed thereon the lock-lugs 24, 24, and the higher actuating lugs 25, 25. The bolt carries the bell crank firing pin 26, pivoted thereto by the screw 27 and moving in the slot 28 in the receiver; the extractor 29 pivoted thereto at 30; and the ejector 31 which has the lug 32 riding in the slot 33 in the receiver. The rear end of the bolt has threaded thereto the bearing member 34 which bears against the recoil spring 35. The rear end of the spring 35 surrounds the buffer 36 and bears against the inner end of the recoil housing 22. The actuator 37' is attached to the bolt and reciprocates the slot 38 formed in the receiver and recoil housing.

The bolt is surrounded by the ring lock 37 which rotates between the thrust rollers 39 and the counter-thrust rollers 40 which bear upon the races 41 and 42 respectively. The inner surface of the ring lock is slotted at 43, 43, to permit the lugs 24 to pass

through when the ring is in the unlocked position. The front of the ring lock is provided with cam surfaces 44, adapted to coact with the cam surfaces 45 of the lugs 24, and the rear face is provided with the cam surfaces 46 to coact with the cams 25. These cam surfaces extend in part above the slotted portions 43 of the ring lock and the lugs 25 are of such height that they cannot pass through the slots but maintain a bearing against the cam surfaces.

The rear of the bolt contains the hand actuator shaft 47 which carries the pin 48 projecting through the quadrant slot 49 in the bolt 23 and entering the axial groove 50 in the ring lock 37. The front end of the shaft 47 has a bearing 51 in the bolt 23 and the reduced rear end has a bearing 52 in the member 34. Surrounding the reduced rear portion of the shaft 47 is the actuator ring 53 into which the actuator 37' is screw-threaded. Passing axially through the actuator 37' is the plunger 54 having the head 55 normally held outward by the spring 56. The inner end of the plunger 54 carries the cone catch 57 and the shaft 47 has the cavity 58 adapted to receive this catch.

The form of lock shown in Fig. 9 is provided with the circumferential groove 60 and the spiral spring 61 fitting therein. One end of the spring is attached to the receiver and the other to the ring lock. The spring is tensioned to normally rotate the ring to the locked position. The action of the locking cams under the powder pressure opens the lock as in the other forms and when the bolt is again closed and the locking lugs clear the ring the spring serves to rotate the ring into locked position. In this form of the device the rear actuating lugs 25 are not needed for the purpose of turning the ring lock but are desirable in order to insure that the lock will not move forward sufficiently to fire the cartridge before the lock has been turned by the spring. The spring may be provided simply as an auxiliary.

The operation of the gun shown is as follows: Starting with the bolt closed and the chamber empty, as shown in Fig. 1, the actuator 37', which is normally horizontal, is rotated 90° until it is vertical, passing through the portion 38' of the slot 38 as shown in Fig. 12. The head 55 is now pressed down which causes the cone catch 57 to interfit with the cavity 58 in the actuator shaft 47. With the head maintained depressed the actuator is rotated downward through 90°, the catch 57 causing the shaft 47 to rotate carrying with it the pin 48 and thereby causing the ring lock 37 to rotate. Due to the relation of the cam surfaces 44 and 45 and 25 and 46, the bolt moves to the rear somewhat on this rotation, the actuator passing down against the rear of the

slot 38' and the pin 48 moving rearwardly in the slot 50. When the actuator reaches the horizontal the cams are as shown in Fig. 10 and upon moving the actuator rearwardly through the slot 38 the bolt moves to the rear as shown in Fig. 2. The pressure upon the head 55 may now be released.

A cartridge will now be placed in front of the bolt 23 by any suitable magazine or feeding means not a part of the present invention, or one may be placed by hand in the chamber if desired.

Upon releasing the actuator 37' the bolt 23 is carried forward by the force of the spring 35. When in its forward motion the cam lug 25 strikes the steel portion 46' of the cam 46 on the rear surface of the ring lock 37 as shown in Fig. 10, the force of the impact is such as to rotate the lock into the position shown in Fig. 11. The ring lock being mounted upon roller bearings takes but little force to rotate it. The cam surface 45 on the lug 25 is cut away at 45' to permit the start of this rotation. During this rotation the interlock between the actuator and actuator shaft having been released, the actuator remains horizontal although due to the interfit between the pin 48 and the ring lock 37 the shaft turns with the ring lock. A small clearance is provided between the shaft 47 and the bolt 23 and ring 53 in order to eliminate friction in this turning movement.

When the ring lock is fully turned into the position shown in Fig. 11 the main portion of the cam surfaces 45 of the lugs 25 are in intimate contact with the locking cam surfaces 44 on the face of the ring lock.

These surfaces are preferably placed upon the Blish angle as defined in the patent to Blish, 1,131,319, of March 9, 1915. This angle is such that the bolt remains locked until the powder pressure in the chamber has been reduced to a safe limit when the cam surfaces move relative to each other and are unlocked by the pressure exerted against the bolt face. At the instant when the lock is complete the upper portion of the bell crank firing pin contacts with the forward end of the groove 28, which forces the lower end of the pin against the primer, firing the cartridge. It will be noted that the upper guide surface of the groove 28 is on an angle such as to prevent the firing point extending out of the bolt face until the bolt is completely closed.

When the chamber pressure is reduced to a working pressure the pressure of the cam surface 45 against the surface 44 turns the ring lock to the unlocked position and the residual pressure is sufficient to cause the bolt to move rearwardly to the position shown in Fig. 2. The empty shell is carried to the rear with the bolt by the extractor 29 and the lug 32 on the ejector

striking the rear end of the groove 33 causes the ejector to be forced forward relative to the bolt and ejects the shell through the side opening 18.

The bolt will again carry a cartridge into the chamber in its forward motion and the operation will continue as long as ammunition is supplied.

The gun shown may be readily assembled and dismantled in but a few minutes. Upon removing the recoil housing from the receiver the recoil spring and buffer may be taken out. By taking out the screw 27 which may readily be done through the ejection opening 18, the bolt may be drawn fully to the rear out of the receiver. The ring lock with its roller bearings and rolls may then be taken out by removing the member 21. The several members going to make up the actuating assembly on the bolt may be readily removed by unscrewing the various connections therebetween as is clearly apparent in Fig. 14.

My improved ring lock and its actuating means, both automatic and manual are independent of the other features of the firearm to which it may be applied. The specific forms shown herewith are illustrative only, it being necessary to show a certain amount of other gun structure to clearly illustrate the application of my invention.

If desired, suitable means may be provided to retain the bolt in its rearward position until released by a trigger or otherwise. This may be done by any suitable means, many of which are known to the art. Such means would operate independently of the lock and forms no part of the present invention.

It should be noted that a cartridge cannot be placed in the chamber and the bolt closed without firing the cartridge, if the form of firing pin shown is used, but it is obvious that if desired the bolt may have a longitudinal passage therein provided with any suitable firing pin operated in any desired manner without in any way modifying the operation of the ring lock.

I claim:

1. In a firearm, a reciprocating bolt, and a locking member adapted to rotate in a plane transverse to the axis of the bolt, said member being restrained from longitudinal movement, and cam surfaces upon the bolt co-operating with cam surfaces upon the forward face of the locking member whereby the locking member is rotated to unlocked position by the rearward movement of the bolt.

2. In a firearm, a reciprocating bolt, and a locking member adapted to rotate in a plane transverse to the axis of the bolt, said member being restrained from longitudinal movement, and cam surfaces upon the bolt co-operating with cam surfaces upon the for-

- ward face of the locking member whereby the locking member is rotated to unlocked position by certain predetermined pressures upon the bolt.
5. 3. In a firearm, a reciprocating bolt, and a rotating locking member, said member being restrained from longitudinal movement, and cam surfaces upon the bolt coöperating with cam surfaces upon the rear face of the locking member whereby the locking member is rotated to locked position by the forward movement of the bolt.
10. 4. In a firearm, a reciprocating bolt, and a rotating locking member, said member being restrained from longitudinal movement, resilient means urging the bolt forward, and cam surfaces upon the bolt coöperating with cam surfaces upon the rear face of the locking member whereby the locking member is rotated to locked position by the forward movement of the bolt caused by said resilient means.
15. 5. In a firearm, a reciprocating bolt, and a rotating locking member, said member being restrained from longitudinal movement, and cam surfaces upon the bolt coöperating with cam surfaces upon the locking member whereby the locking member is rotated to unlocked position by certain predetermined pressures upon the bolt, resilient means urging the bolt forward, and other cam surfaces upon the bolt coöperating with cam surfaces upon the lock whereby the locking member is rotated to locked position by the forward movement of the bolt caused by said resilient means.
20. 6. In a firearm a reciprocating bolt and a rotating locking member, cam surfaces upon the bolt adapted to coöperate with cam surfaces upon the locking member, the meeting surfaces being oblique and upon such an angle as to maintain the surfaces in fixed relation under initial powder pressure but to permit relative movement when the powder pressure has reduced to a predetermined point.
25. 7. In a firearm, a reciprocating bolt and a rotating locking member, cam lugs adapted to lock the bolt relative to the locking member and rolling bearings in the rear of the locking member adapted to receive the thrust due to powder pressure transmitted from the bolt to the lock.
30. 8. In a firearm, a reciprocating bolt and a rotating locking member, cam lugs adapted to lock the bolt relative to the locking member and frusto-conical bearings in the rear of the locking member adapted to receive the thrust due to powder pressure transmitted from the bolt to the lock, said bearings being further adapted to reduce the friction due to the rotation of the lock.
35. 9. In a firearm, a reciprocating bolt and a rotating locking member, the locking member having frusto-conical front and rear faces, said faces being supported by thrust bearings adapted to reduce the friction of rotation.
40. 10. In a firearm, a reciprocating bolt, a rotating locking member restrained against longitudinal movement and an actuator adapted to reciprocate said bolt and positively to rotate said locking member.
45. 11. In a firearm, a reciprocating bolt, a rotating locking member and an actuator adapted to reciprocate said bolt and positively to rotate said locking member, said actuator being normally disconnected from the locking member.
50. 12. In a firearm, a reciprocating bolt, a rotating locking member, a slot upon the locking member, a pin fitting therein, said pin being attached to an actuator shaft, an actuator, and means to detachably connect said actuator to said actuator shaft whereby movement of said actuator may be transmitted to the locking member through the actuator shaft, the pin, and the slot and thereby to rotate said locking member to the unlocked position.
55. 13. In a firearm, a reciprocating bolt, a rotating locking member, a slot upon the inner surface of the locking member, a pin fitting therein, said pin being attached to an actuator shaft, the actuator shaft being contained in the bolt and the pin extending laterally through the bolt, an actuator, and means to detachably connect said actuator to said actuator shaft, whereby movement of said actuator may be transmitted to the locking member through the actuator shaft, the pin, and the slot and thereby to rotate said locking member to the unlocked position.
60. 14. In a firearm, a reciprocating bolt and a rotating locking member encircling the bolt, longitudinally extending locking lugs upon said bolt, cam surfaces on the front faces of the locking member adapted to coöperate with the rear faces of the locking lugs when said locking member is in the locked position, grooves in the locking member adapted to permit the locking lugs to extend through said member when in the unlocked position, and to thereby restrain it from rotation.
65. 15. In a firearm, a reciprocating bolt and a rotating locking member encircling the bolt, actuating lugs upon the bolt and cam surfaces on the rear face of the locking member adapted to coöperate therewith whereby the said actuating lugs will cause the locking member to rotate from the unlocked to the locked position when the bolt is moved forward into closed position.
70. 16. In a firearm, a reciprocating bolt and a rotating locking member encircling the bolt, longitudinally extending locking lugs upon said bolt, cam surfaces on the front faces of the locking member adapted to coöperate with the rear faces of the locking member having frusto-conical front and rear faces, said faces being supported by thrust bearings adapted to reduce the friction of rotation.

- lugs when said locking member is in the locked position, grooves in the locking member adapted to permit the locking lugs to pass through said member when in the unlocked position, actuating lugs upon the bolt and cam surfaces on the rear face of the locking member adapted to coöperate therewith whereby the said actuating lugs will cause the locking member to rotate from the unlocked to the locked position when the bolt is moved forward into closed position.
17. In a firearm, a reciprocating bolt and a rotating locking member encircling the bolt, longitudinally extending locking lugs upon said bolt, cam surfaces on the front faces of the locking member adapted to coöperate with the rear faces of the locking lugs when said locking member is in the locked position, grooves in the locking member adapted to permit the locking lugs to pass through said member when in the unlocked position, actuating lugs upon the bolt and cam surfaces on the rear face of the locking member adapted to coöperate therewith whereby the said actuating lugs will cause the locking member to rotate from the unlocked to the locked position when the bolt is moved forward into closed position.
18. In a firearm, a reciprocating bolt and a rotating locking member encircling the bolt, longitudinally extending locking lugs upon said bolt, cam surfaces on the front faces of the locking member adapted to coöperate with the rear faces of the locking lugs when said locking member is in the locked position, grooves in the locking member adapted to permit the locking lugs to pass through said member when in the unlocked position, actuating lugs upon the bolt and cam surfaces on the rear face of the locking member adapted to permit the locking lugs to pass through said member when in the unlocked position, actuating lugs upon the bolt and cam surfaces on the rear face of the locking member adapted to coöperate therewith whereby the said actuating lugs will cause the locking member to rotate from the unlocked to the locked position when the bolt is moved forward into closed position, the locking lugs fitting in the grooves in the locking member and maintaining that member in unlocked position substantially until the actuating lugs contact with their coöperating cams.
19. In a firearm, a reciprocating bolt and a rotating locking member restrained against longitudinal movement and having a torsion spring associated therewith and adapted to normally maintain the lock in locked position.
20. In a firearm, a reciprocating bolt, and a rotating locking member, said member being restrained from longitudinal movement and being so associated with the bolt as to be rotated from locked to unlocked position by the rearward movement of the bolt, and a torsion spring associated with the locking member and adapted to rotate the said member from unlocked to locked position.
21. In a firearm, a reciprocating bolt, a rotating locking member, said member being restrained from longitudinal movement and being so associated with the bolt as to be rotated from locked to unlocked position by the rearward movement of the bolt, and a torsion spring seated in a circumferential groove about said locking member and adapted to rotate the said member from unlocked to locked position.
- Signed by me at New Canaan, Connecticut this 21st day of February, 1920.

JOHN T. THOMPSON.
